UNITED STATES PATENT OFFICE.

FRANK L. ZYBACH, OF GRAND ISLAND, NEBRASKA, ASSIGNOR OF ONE-HALF TO
EDWARD P. RYAN, OF GRAND ISLAND, NEBRASKA.

WALKING DOLL.

Application filed February 23, 1926. Serial No. 90,202.

This invention relates to improvements in walking dolls.

An important object of the invention is to provide in a construction of this character means whereby the doll may walk with a stride simulating the ordinary walking stride of human beings together with means for balancing the doll while walking.

A further object of the invention is to provide means whereby the balancing element acts to relieve the mechanism by which the stride is effected of a portion of the weight of the doll.

A further object of the invention is to provide a device of this character which may be readily and cheaply produced, which will be durable and efficient in service and a general improvement in the art.

A still further object of the invention is to provide a device of this character in which the legs of the doll may be moved to horizontal position to allow the doll to assume a sitting position, when this is desired, and to provide means whereby the balancing element may be readily removed from the doll when the doll is to assume the sitting position.

A further object of the invention is to provide in combination a walking doll and a sulky or similar implement which the doll pushes while walking, the sulky acting to steady the doll and balance the same and likewise acting to relieve the legs of the doll of a portion of the weight of the body and of the operating mechanism whereby the walking action is effected.

These and other objects I attain by the construction shown in the accompanying drawings, wherein for the purpose of illustration is shown a preferred embodiment of my invention and wherein:—

Figure 1 is a side elevation partially broken away of a doll constructed in accordance with my invention;

Figure 2 is a front elevation of the operating mechanism of the doll;

Figure 3 is a section on the line 3—3 of Figure 2;

Figure 4 is an enlarged view showing the mounting of the legs;

Figure 5 is a detail sectional view showing the construction of the sulky whereby a portion of the weight of the doll is counterbalanced.

Referring now more particularly to the

drawings, the numeral 10 generally designates the body of a doll within which is arranged a framework including upper and lower substantially oval frame members 11 and 12 and vertical side frame members 13 connecting the frame members 11 and 12 and providing a support for the mechanism, hereinafter to be described.

Means for attaching the upper and lower ends of the side frame members 13 to the frame members 11 and 12 includes bolts 14. About the bolts intermediate the side frame members 13 are arranged spacers 15 for holding the frame in properly spaced relation. The upper and lower frame members 11 and 12 provide means for attaching the mechanism to the body of the doll. Rotatably mounted in the side frame members 13 is a transversely extending shaft 16, one end of which projects to one side of the frame members and is provided with a squared end 17 for the reception of a crank whereby it may be rotated. This shaft has secured thereto one end of a clock spring 18, the opposite end of which is attached to the upper bolt 14 connecting the frame members 11 and 13. Secured to the shaft is a ratchet disk 19 having engaged therewith a pawl 20 carried by a drive gear 21. This drive gear 21 meshes with a pinion 22 secured to a shaft 23 mounted in the side frame members 13 and having its ends projected therebeyond and formed with cranks 24. The shaft 23 has secured thereto a gear wheel 25 which meshes with a pinion 26 upon a shaft 27 rotatably mounted between the lower ends of the side frame members 13. This shaft adjacent one of the frame members is provided with a pivot 28 upon which is mounted a governor element 29 including a tail 30 which is normally in slightly spaced relation to the adjacent side member 13. This tail is held in this normal position by a spring 31. When the weight 32 of the governor moves outwardly to a predetermined extent from the shaft against the action of the spring 31, the tail 30 comes into engagement with the adjacent side member 13, applying a braking effect to the shaft 27 and accordingly to the entire mechanism. The shaft 27 is further provided with a fly wheel 33 having associated therewith a braking element 34 which is operable from the exterior of the body of the doll, as at 35, to move against the pe-

110

riphery of the fly wheel and check motion of the mechanism.

Arranged upon the outer surface of each side member 18 immediately above the 5 crank shaft and vertically aligned with the crank shaft 23 is a pivot 36. This pivot extends through a slot 37 formed in the upper end of a leg 38 and this leg has an opening 39 receiving the crank 24 at the 10 corresponding end of the crank shaft 23. The legs 38 are preferably formed in two sections 38^a, 38^b having pivotal connection with one another at 40 so that they may be moved to a position, which is illustrated by 15 dotted lines in Figure 3 to permit the doll to be seated upon the floor. The sections of the joint have frictional engagement with one another, resisting movement of the legs from one position to another so that accidental collapse of the legs during walking operation is prevented.

In combination with the doll a sulky 41 is provided having a wheel supported axle 42 and a body structure 43 arranged at one 25 side of the wheel-supported axle. Included in this body structure is a counterweight 44 of desired size. The sulky has substantially parallel handles 45, the ends of which are entered in sockets 46 formed in the ends 30 of the arms 47 of the doll for a distance to render the handles of the sulky rigid to these arms. The sulky arms may, however, be removed from the sockets to separate the elements, as desired.

35 In the operation of the doll, the sulky not only serves to provide a balance for the body 10 but likewise serves to support a portion of the weight thereof because of the provision of the counterweight 44. The crank 40 connections of the legs cause the legs to oscillate and to be alternately lifted and depressed with the result that the weight of the body is supported from first one leg and then from the other and the body advanced 45 by the leg which is supporting it. The speed of operation is controlled from the governor 29.

Since the construction hereinbefore set forth is obviously capable of a certain range 50 of change and modification without materi-

ally departing from the spirit of the invention, I do not limit myself to such specific structure except as hereinafter claimed.

I claim:

1. In a walking doll, a body including a 55 framework having transversely spaced side members, legs having pin and slot engagement at their upper ends with said side members, a shaft rotatably mounted in said side members below the point of connection of 60 the legs therewith, said shaft at each end thereof having a crank rotatably engaged in the associated leg, a motor supported from the frame for driving the crank shaft, means for controlling the speed of rotation of the 65 crank shaft including a shaft driven from the crank shaft and having its ends rotatably supported by the side members, a governor element pivoted to said shaft and having a heel opposing the inner face of 70 one of the side members at one end and at its opposite end a weight and a spring, normally maintaining the weighted end in engagement with the shaft.

2. In a walking doll, a body including a 75 framework having transversely spaced side members, legs having pin and slot engagement at their upper ends with said side members, a shaft rotatably mounted in said side members below the point of connection 80 of the legs therewith, said shaft at each end thereof having a crank rotatably engaged in the associated leg, a motor supported from the frame for driving the crank shaft, means for controlling the speed of rotation 85 of the crank shaft including a shaft driven from the crank shaft and having its ends rotatably supported by the side members, a governor element pivoted to said shaft and having a heel opposing the inner face of one 90 of the side members at one end and at its opposite end a weight, a spring normally maintaining the weighted end in engagement with the shaft, a fly wheel mounted on said shaft and a brake mechanism engaging said 95 fly wheel.

In testimony whereof I hereunto affix my signature.

FRANK L. ZYBACH.
